United States Patent Office

Des. 183,118
Patented July 1, 1958

183,118

RESTAURANT OR SIMILAR ARTICLE

James D. Comstock, Houston, Tex.

Application January 28, 1957, Serial No. 44,632

Term of patent 14 years

(Cl. D13—1)

Fig. 1

Fig. 2

Fig. 3

Fig. 4

The side of the design not shown is the same as the side shown in Figure 3.

I claim:

The ornamental design for a restaurant or similar article, as shown and described.
